US0D1062619S

(12) **United States Design Patent** (10) **Patent No.:** **US D1,062,619 S**
(45) **Date of Patent:** **** Feb. 18, 2025**

(54) **MULTIFUNCTIONAL WIRELESS CHARGING DOCKING STATION**

(71) Applicant: **Qianhai Junda (Shenzhen) Equity Investment Co., Ltd**, Shenzhen (CN)

(72) Inventor: **Zhuowen Liao**, Shenzhen (CN)

(73) Assignee: **Qianhai Jonda (Shenzhen) Equity Investment Co., Ltd**, Shenzhen (CN)

(**) Term: **15 Years**

(21) Appl. No.: **29/869,726**

(22) Filed: **Jan. 6, 2023**

(30) **Foreign Application Priority Data**

Jul. 13, 2022 (CN) 202230443721.5

(51) **LOC (15) Cl.** **13-02**

(57) **CLAIM**

The ornamental design for a multifunctional wireless charging docking station, as shown and described.

DESCRIPTION

FIG. 1 is a front, left and bottom perspective view of a multifunctional wireless charging docking station showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the multifunctional wireless charging docking station that form no part of the claimed design.

1 Claim, 7 Drawing Sheets
